CLAIM

The ornamental design for a device for sliding furniture on the floor and carpet, as shown and described.

DESCRIPTION

FIG. 1 is a front perspective view of a device for sliding furniture on the floor and carpet, showing my new design; FIG. 2 is a rear perspective view thereof; FIG. 3 is a front elevational view thereof; FIG. 4 is a rear elevational view thereof; FIG. 5 is a right-side elevational view thereof; FIG. 6 is a left-side elevational view thereof; FIG. 7 is a top plan view thereof; FIG. 8 is a bottom plan view thereof; and, FIG. 9 is an enlarged view of detail 9 of FIG. 5. The broken lines show portions of the device for sliding furniture on the floor and carpet that form no part of the claimed design. The broken lines consisting of short and long dash lines encircling the enlarged detail views are for annotative purposes and form no part of the claimed design.
